COMBINED CLOCK AND WHAT-NOT SHELVES

Benjamin G. Edelman, Brooklyn, N.Y., assignor to United Metal Goods Manufacturing Co., Inc., Brooklyn, N.Y., a corporation of New York

Filed Nov. 1, 1968, Ser. No. 14,272

Term of patent 7 years

Int. Cl. D10—01

U.S. Cl. D42—7

FIG. 1 is a front elevational view of a combined clock and what-not shelves showing my new design,

FIG. 2 is a top plan view,

FIG. 3 is a right side elevational view,

I claim:

The ornamental design for a combined clock and what-not shelves, substantially as shown.
